UNITED STATES PATENT OFFICE.

WILLIAM A. FULD, OF BALTIMORE, MARYLAND.

FIGURE WHEELED TOY.

Application filed January 5, 1928. Serial No. 244,670.

This invention relates to toys and has among its objects the provision of a toy animal or bird when drawn along a suitable support will sway from side to side in simulation of the natural body movement of that animal or bird in walking.

Another object of the invention is to so mount the head that it will sway in synchronism with the body.

10 Still another object is to so mount the tail that it will swing in synchronism with the body.

One form of a structure whereby the foregoing objects are attained is illustrated in 15 the accompanying drawing in which

Figure 1 is a side elevation;

Fig. 2 is a top plan view, and

Fig. 3 is an end elevation.

Referring to the drawing more specifically, 20 10 is the body portion of an animal, the instant animal being a bear, having legs 11, the feet of which are provided with journals in which shafts 12 and 13 are loosely mounted. Wheels 14 are rigidly mounted on shaft 12 25 at their axes. Wheels 15 are rigidly mounted on shaft 13 off center and diametrically out of register for a reason which will appear later.

The head 16 is loosely mounted on pin 17 30 so that it is free to swing from side to side. A cord, or other flexible member, is attached to the end of pin 17 for the purpose of drawing the object along a support.

A tail 18 is loosely mounted on pin 19 so 35 that it also is free to swing from side to side. Stability is given to the toy by reason of the fact that the wheels are relatively far apart and are so held apart by spacers 20.

Having in mind the foregoing description, 40 the manner in which my toy operates will now be described.

The front wheels being mounted on shaft 13 off center at diametrically opposite points cause the top part of the body to move from 45 side to side. This movement is magnified by reason of the fact that the journal openings loosely house the shafts 12 and 13.

Because the head and tail are mounted with their center of gravity well below the 50 mounting pin this swaying, or reciprocating, motion of the body causes the head and tail to swing from side to side as the toy is pulled along its support.

This combination of the sway of the body 55 and swing of the head and tail gives an effect very much like the lumbering ambling gait

of such heavy animals as bears and elephants.

It is obvious that minor changes of details of construction come within the purview of 60 this invention.

I claim:

1. A toy comprising, in combination, a body simulating an animal, front and rear shafts loosely journaled therein, wheels 65 rigidly mounted on said shafts the wheels on one of said shafts being mounted off-center in diametrically opposite directions so that the body will sway from side to side as the toy is drawn along, and a body member 70 loosely mounted above its center of gravity on said body on an axis extending substantially horizontally and longitudinally of the body, whereby the body member will sway from side to side through the swaying of 75 the body and means for drawing said toy along a support.

2. A toy comprising, in combination, a body simulating an animal, front and rear shafts loosely journaled in the feet thereof, 80 supporting wheels rigidly mounted on said shafts, spacers between said wheels and said feet, the wheels on one of said shafts being mounted off-center in diametrically opposite directions so that the body will sway 85 from side to side as the toy is drawn along, head and tail members each loosely mounted above its center of gravity on said body on an axis extending substantially horizontally and longitudinally of the body, whereby the 90 body member will sway from side to side through the swaying of the body, and means for drawing said toy along a support.

3. A toy comprising, in combination, a body simulating an animal, front and rear shafts loosely journaled in the feet thereof, 95 supporting wheels rigidly mounted on said shafts, spacers between said wheels and said feet, the wheels on the front shaft being mounted off-center in diametrically opposite 100 directions so that the body will sway from side to side as the toy is drawn along, a head member loosely mounted above its center of gravity on said body, on an axis extending substantially horizontally and longitudinally 105 of the body, whereby the body member will sway from side to side through the swaying of the body and means for drawing said toy along a support.

4. A toy comprising, in combination, a 110 body simulating an animal, front and rear shafts loosely journaled in the feet thereof,

supporting wheels rigidly secured to the ends of said shafts, spacers on said shafts between said wheels and said feet, the wheels on the front shaft being equally mounted off-center in diametrically opposite directions so that the body will sway from side to side as the toy is drawn along, head and

tail members each mounted above its center of gravity on said body to freely swing from side to side through the swaying of the body and means for drawing said body along a support.

WILLIAM A. FULD.
